(57) **CLAIM**

The ornamental design for a display screen for a marine drive, as shown and described.

DESCRIPTION

FIG. 1 is a front perspective view of a display screen for a marine vessel according to our new and ornamental design.

FIG. 2 is a side view thereof.

FIG. 3 is an opposite side view thereof.

FIG. 4 is a front view thereof.

FIG. 5 is a rear view thereof.

FIG. 6 is a top view thereof; and,
FIG. 7 is a bottom view thereof.

The broken lines illustrate the aspects of the display screen for a marine drive which are not part of the claimed design.
